No. 734,779.

PATENTED JULY 28, 1903.

W. H. VIVIAN.

CANNON.

APPLICATION FILED NOV. 24, 1902.

NO MODEL.

UNITED STATES PATENT OFFICE.

WILLIAM H. VIVIAN, OF GLOUCESTER, MASSACHUSETTS.

CANNON.

SPECIFICATION forming part of Letters Patent No. 734,779, dated July 28, 1903.

Application filed November 24, 1902. Serial No. 132,528. (No model.)

To all whom it may concern:

Be it known that I, WILLIAM H. VIVIAN, a citizen of the United States, residing at Gloucester, in the county of Essex and State of Massachusetts, have invented new and useful Improvements in Cannon, of which the following is a specification.

This invention relates to improvements in cannon for war-ships or field-pieces in which the supporting-carriage of the cannon, not resting upon a stationary fixed base, assumes different angles, the object of the invention being to so support a cannon that said cannon and the front and rear sights thereof shall always maintain the same relation to a vertical plane extending through the longitudinal median line of said cannon, so that as the carriage upon which the cannon is supported assumes different angles according to the motion of the vessel the cannon maintains the same relative position to said vertical plane and the conditions under which the cannon is sighted remain constant, thus greatly increasing the accuracy with which the cannon can be aimed either, as hereinbefore stated, on a vessel or when mounted upon a carriage for field-pieces.

The invention consists in a cannon, a sleeve eccentrically mounted thereon, and a suitable support upon which said sleeve is rotatably mounted.

The invention again consists in a cannon, a sleeve eccentrically mounted thereon, and an annular ring in which said sleeve is rotatably mounted.

The invention finally consists in the combination and arrangement of parts set forth in the following specification, and particularly pointed out in the claims thereof.

Referring to the drawings, Figure 1 is a side elevation of a cannon mounted in accordance with my invention. Fig. 2 is a rear end elevation of the same, showing the base of the carriage resting in a horizontal plane. Fig. 3 is a rear elevation similar to Fig. 2, illustrating the base of the carriage tilted at an angle, while the cannon remains in the same position with relation to a vertical plane extending through the longitudinal median line and through the sights as that shown in Fig. 2. Fig. 4 is a longitudinal section, partly in elevation, taken on line 4-4 of Fig. 2. Fig. 5 is a detail elevation of the front sight and a

portion of one of the eccentric flanges. Fig. 6 is an enlarged detail elevation of the rear sight and a portion of the rear eccentric flange. Fig. 7 is an enlarged detail section of a portion of the rear eccentric flange, annular ring, and roller-bearings.

Like numerals refer to like parts throughout the several views of the drawings.

In the drawings, 8 is a cannon of ordinary construction. 9 is a sleeve surrounding said cannon, in which said cannon is arranged to slide longitudinally.

10 10 are ears fast to the cannon 8 and having recoil-cylinders 11-11 fast thereto. The pistons of the recoil-cylinders are fastened by the rods 12-12 to the rear eccentric flange 13, integral with the sleeve 9. The interior construction of the recoil-cylinders is not illustrated in the drawings; as it forms no part of this invention and is well known to those skilled in the art. The rear eccentric flange 13 and front eccentric flange 14 are both integral with the sleeve 9 and eccentric to the bore of the cannon 8. Said flanges are rotatably mounted in an annular ring 15, formed in two parts joined together by cross-pieces 16-16. The cross-pieces 16 are provided with trunnions 17, integral therewith and pivotally mounted upon the cheeks 18 of the carriage 19. The carriage 19 is preferably formed in two parts, the upper part 20 constituting a table arranged to rotate in a horizontal plane upon the base 21. In the said rear eccentric flange 13 is provided a vertical slot 22 extending therethrough, and upon the rear face of the flange 13 is fastened a plate 23, provided with a slide 24, constituting the rear sight. Said slide 24 is provided with a sight-hole 25 and with a thumb-screw 26, by which it is held in fixed relation to the plate 23, the slide 24 projecting into the slot 22. The front eccentric flange 14 is provided with an aperture 27, and in this aperture is located the stationary front sight 28.

In order that the sleeve 9 and the flanges 13 and 14 may rotate within the ring 15 with the least possible friction, roller-bearings 29 and 30 are provided, the roller-bearings 29 being located between the periphery of the eccentric cylindrical flange 13 and the ring 15. End roller-bearings 30 are provided between one face of the flange 13, adjacent to

- the periphery thereof, and a plate 31, fast to the ring 15 by screw-bolts 32. The rollers of the bearing 29 are held in position laterally by means of a plate 33, held to the ring 15 by screw-bolts 34. Roller-bearings 35 are also provided (see Fig. 4) between the forward eccentric flange 14 and the ring 15, the rollers of said bearing being held in position by plates 36 and 37, fast to the ring 15 by screw-bolts.
- 10 The operation of the cannon, mounted as hereinbefore described, is as follows: The cannon is free to slide longitudinally in the sleeve 9 and is controlled by the recoil-cylinders 11, 11 in the usual manner. When the vessel rolls, the base 21 may be moved from the position shown in Fig. 2 to that shown in Fig. 3, and in this case the cannon 8, together with the sleeve 9 and the flanges 13 and 14 integral therewith, maintains the same position with relation to a vertical plane passing through the median line of the bore of the cannon, so that the conditions and the position of the sight are always the same with relation to the cannon and with relation to said vertical plane, as illustrated in Fig. 3, in which the slot 22 is shown to be vertical and lies in the vertical plane passing through the longitudinal median line of the bore of the cannon, the same as in Fig. 2, in which the base 21 is horizontal. It will therefore be seen that as the support upon which the base 21 rests assumes different angles, either when said support is a vessel or when it is the carriage of a field-piece, the cannon and the sleeve surrounding said cannon will always maintain the same relation to a vertical plane passing through the longitudinal median line of the bore of said cannon and that the sights will also maintain the same relative location in relation to said plane, and therefore that under all conditions the accuracy with which the cannon can be aimed in using the front and rear sights is not interfered with.
- 45 It will be seen that while I have illustrated the sleeve 9 as provided with two eccentric flanges 13 and 14 for the sake of convenience in construction and for saving metal said sleeve might be made as a cylinder without

flanges, the periphery of said cylinder being 50 of the diameter of said flanges, and the cannon eccentrically mounted in said sleeve with relation to the periphery thereof without departing from the spirit of my invention.

Having thus described my invention, what 55 I claim, and desire by Letters Patent to secure, is—

1. A cannon, a cylindrical sleeve eccentrically mounted thereon, and a suitable support upon which said sleeve is rotatably mounted. 60

2. A cannon, a cylindrical sleeve eccentrically mounted thereon, and an annular ring in which said sleeve is rotatably mounted.

3. A cannon, a sleeve mounted thereon, cylindrical flanges upon said sleeve eccentric to 65 the bore of said cannon, and an annular ring in which said flanges are rotatably mounted.

4. A cannon, a sleeve mounted thereon, cylindrical flanges upon said sleeve eccentric to 70 the bore of said cannon, an annular ring in which said flanges are rotatably mounted, trunnions integral with said annular ring, and a carriage upon which said trunnions are pivotally mounted.

5. A gun-carriage, an annular ring pivotally supported thereon, and a cannon rotatably and eccentrically mounted within said ring. 75

6. A cannon, a sleeve mounted thereon, two cylindrical flanges integral with said sleeve 80 eccentric to the bore of said cannon, said flanges provided with apertures to receive a front and a rear sight, and an annular ring in which said flanges are rotatably mounted.

7. A cannon, a sleeve mounted thereon, cylindrical flanges upon said sleeve eccentric to 85 the bore of said cannon, an annular ring in which said flanges are rotatably mounted, and roller-bearings interposed between said flanges and ring.

In testimony whereof I have hereunto set my hand in presence of two subscribing witnesses.

WILLIAM H. VIVIAN.
